UNITED STATES PATENT OFFICE.

JAMES H. HORNE, OF DAYTON, OHIO, ASSIGNOR TO THE BARNEY & SMITH CAR COMPANY, OF SAME PLACE.

DESIGN FOR A BUFFET.

SPECIFICATION forming part of Design No. 32,098, dated January 9, 1900.

Application filed December 1, 1899. Serial No. 738,926. Term of patent 7 years.

To all whom it may concern:

Be it known that I, JAMES H. HORNE, a citizen of the United States, residing at Dayton, in the county of Montgomery and State of Ohio, have invented and produced a new and original Design for a Buffet, of which the following is a specification, reference being had to the accompanying drawings, forming part thereof.

In the accompanying drawings, Figure 1 is a front perspective view of a buffet, showing my new design. Fig. 2 is a side elevation, and Fig. 3 a top view thereof.

The leading or material features of my design consist in the configuration or contour of the top for a buffet and in its general outline from top to bottom through the center line of Fig. 1, as seen in Fig. 2.

In the said drawings similar letters of reference indicate corresponding parts throughout the several figures.

A represents the base or lower portion, and B an upper overhanging portion supported by a back C. The said base or lower portion

is provided with doors D, and the said upper overhanging portion is provided with doors E, provided with cathedral or other ornamen-

tal glasswork, as shown. At the bottom of the overhanging portion B there is a molding a, and the top thereof is finished with a suitable molding b, the latter forming a base for a top F, which consists of a segment of a sphere, the same being substantially a quarter-section thereof and which is represented as being composed of sections of cathedral or art glass.

The top of the lower portion A consists of a shelf G, which projects slightly beyond the said portion A, as shown at c, and which is provided with a railing d. Between the said portions A and B and at the back of space H, formed thereby, there is a mirror I, intended to contribute a pleasing effect, particularly when silverware or other articles are exposed on the shelf G.

I claim—

The design for a buffet, substantially as herein shown and described.

In testimony whereof I hereunto subscribe my name this 29th day of November, 1899.

J. H. HORNE.
